SHEET-METAL EVAPORATOR

Delos P. Heath, Detroit, Mich., assignor, by
mesne assignments, to General Motors Corpora-
tion, a corporation of Delaware

Application April 9, 1931, Serial No. 528,847

8 Claims. (Cl. 62—126)

It is an object to provide a process of making a sheet metal evaporator from a thin walled structure one of whose walls is corrugated and formed into a U-shape by a die in a single forming operation.

It is an object to provide a sheet metal evaporator enclosing a freezing chamber, which evaporator will comprise a minimum number of parts and which will allow a maximum economy in its complete manufacture by the stamping and the welding processes.

In the drawings:

Figure 1 is a front elevation of the outer shell of the evaporator after the forming operation.

Figure 2 is a side elevation of Figure 1, and also shows in dotted lines a modification of the header portion.

Figure 3 is a front elevation of the inner shell of the evaporator after the forming operation and also shows in dotted lines a modification of the portion of the sheet connecting the side walls.

Figure 4 is a front elevation of the assembled evaporator.

Figure 5 is a partial vertical section through Figure 4 at A—A.

Figure 6 is a partial vertical section through Figure 4 at B—B.

Figure 7 shows a modification of Figure 1 with flanges.

Figure 8 illustrates the side elevation of Figure 7.

Figure 9 shows the evaporator of Figure 7 assembled with an inner shell, a modification of Figure 3, to form the expansion chamber of a re-
movable integral refrigerating unit.

Figure 10 is a plan view of the flanged outer shell shown in Figure 7 assembled with its flanged inner shell.

Fig. 11 is a detail of welding flanged ends; and

Fig. 12 is a modified view of the evaporator disclosed in Fig. 9 showing a pipe secured to the walls of the structure and providing communication between the headers formed at the top of the evaporator.

The like numerals refer to like parts.

I have already shown in my Patent Number 1,726,486 dated August 27, 1929, a U-shaped sheet metal evaporator enclosing a freezing space which generally resembles the evaporator shown in Figure 4, but the present invention provides simpler and less costly methods of manufacture, while at the same time allowing an evaporator of the same efficiency. Also in my application number 75,325 of December 14, 1925, I have dis-

closed an evaporator of general construction illustrated in Figure 9.

Numeral 1 indicates a thin metallic sheet preferably of a steel suitable for deep drawing and which may be protected against corrosion. A 5 plurality of corrugations, 2, may be formed with the header portions, 4 and 5, communicating therewith, in one stamping operation at the same time the sheet is formed into a U-shaped structure as shown in Figure 1. 3 indicates flat portions of 1 between the corrugations. These flat portions lie in substantially the same line with each other and with the peripheries 7.

The inner shell 8, Figure 3, being formed in a U-shape similar to Figure 1 in section, the peripheries 7 on two sides of the shells 1 and 8 may be assembled continuously contiguous at the front and back of assemblies, Figs. 4 and 9.

As a modification the header portion of sheets 1 and 8 may be formed as true cylindrical shapes 20 extending to the front and back edges as indicated by the dotted lines in Figure 2. However, with this modification, as in my Patent Number 1,726,486 dated August 27, 1929, it will be necessary to provide additional closure means at the 25 ends of the header. The side walls of the shells 1 and 8 may be connected by a plain surface portion as shown in Figure 9, or by an arcuate surface portion as shown in Figures 1 and 3. It is also possible to indent in initially forming the 30 connecting portion of 8 between the side walls, to provide additional strength and volume as shown dotted in Figures 3 and 4.

After 1 and 8 are formed and super-imposed together the contiguous portions 3 and 7 of 1 are 35 welded to 8 by the spot welding or seam-welding process. It may also be desirable to fasten these contiguous portions together by other means, such as, copper brazing.

To obtain the evaporator of Figure 4, the short 40 portion, 10, of the welded assembly of sheets 1 and 8, is formed inwardly until the edges of the walls meet to form a small semi-cylindrical header, 4. The bottom edges of the inner sheet 8 and the outer sheet, 1, are welded together to form a 45 fluid tight chamber.

Opening 11 may be provided in 5 or in 4, for the admission of refrigerant, and an opening 11, may be provided in 5 for the outlet of expanded refrigerant gas.

Trays 12 shown dotted in Figure 4 may be inserted between the walls of the evaporator for the production of ice, and for quick freezing processes these trays may rest upon the bottom portion of the inner shell 8.

50

55

Figure 9 shows the sheet metal tray shelf 13, which may be either fixed to or removable from the side walls, but it is preferably in close heat conducting contact with the walls of shell 8 to permit the removal of heat from 12 at a rapid rate.

Numerals 14 designate flanges formed outwardly at the upper ends of shells 1 and 8 as shown in Figures 7, 8, 9, 10, to provide sealing means and if desired supporting means for the two shells. 15, are slots stamped out of 14 to conveniently receive screws, rivets, or bolts, 17, which may removably or permanently fasten the evaporator to the insulated removable refrigerating machine base, 16, as shown in Figure 9. In this latter figure the numeral 18, indicates a condensing unit mounted on 16, and operatively connected to the sheet metal evaporator, formed by shells 1 and 8, and to the high pressure float valve, 19. This 20 cooling apparatus may be inserted in an opening in the refrigerator, 21 or removed therefrom as an integral unit.

Member 20 is a tube leading refrigerant liquid from the float valve 19 through the inlet 11 of the flange 14 at the top of shell 8, to the bottom of the evaporator.

In the modified showing, Fig. 12, of the evaporator structure disclosed in Fig. 9, 22 designates a refrigerant header pipe that may be welded gas tight near the top of the side walls of shell 8, Figure 9, to provide free fluid flow and additional gas and liquid space between the headers, 4. If this pipe 22 is built into the evaporator as shown in Fig. 12 is also eliminates the necessity of two evaporator outlets and serves to stiffen the structure.

23 is the suction pipe connecting the condensing unit 18 to the outlet opening 11 in the flange 14 of the sheet 8.

40 In operation refrigerant gas occupying space between sheets 1 and 8 is withdrawn by the condensing unit 18 through suction pipe 23, and condensed to a liquid. Liquid refrigerant accumulating in 19 raises the float to admit the liquid through inlet tube 20, to the bottom of the expansion chamber. This liquid freely circulates through the corrugations 2, and the headers 4 and 5, in contact with the shells 1 and 8, to receive refrigerator heat energy through 45 these metallic walls. When the liquid becomes superheated gas bubbles form and rapidly rise to the headers 4 of Figure 9, and the header 5, of Figure 4.

In both the evaporators shown, the refrigerant liquid and gas may freely flow at the bottom of the evaporator between the side walls, however, in Figure 11 is shown a modification of the method of joining the bottom ends of the two sheets 1 and 8. Whereas, in Figure 4 these 55 sheets form a semi-cylindrical header 4, in a modification, flanges are formed on the ends of the shells in Figures 1 and 3 as illustrated in Figure 7. These flanges are welded together gas tight, as shown in Figure 9, and after forming the portions 10 the flanges are abutted and welded together.

Although Figures 4 and 9 show the side walls of shells 1 and 8 formed at right angles to the portions 10 and 6 respectively, it is entirely practicable to assemble shells 1 and 8 by the welding process and to use them as a complete evaporator while retaining the slight angle of draft required in the forming operation.

I have described a particular use of the invention in the manufacture of evaporators for re-

frigerators, but I do not wish to limit the scope of the invention to this use as it may be employed in forming corrugated wall structure pressure vessels for many other purposes.

I claim:

1. A cooling unit for mechanical refrigeration comprising, an inner one piece shell bent to form walls enclosing a horizontal ice freezing chamber or chambers, an outer one piece shell having an arcuate gas liquid header portion and side 10 walls extending therefrom along the top, the sides and the bottom of the said inner shell freezing chamber walls and terminating with arcuate liquid header portions at its ends, said outer shell header portions forming with portions of 15 the inner shell a gas liquid header at one side of the freezing chamber and a liquid header at the opposite side of said chamber, the ends of the inner shell spaced from the gas liquid header being welded to each other and the arcuate portions of the outer shell liquid header walls being 20 welded together, one of said shells being embossed to provide refrigerant passage ways connecting said liquid header with said gas liquid header to form an expansion chamber for refrigerant.

2. A cooling unit for a refrigerating apparatus comprising, an inner one-piece shell bent to form walls of a horizontal freezing chamber or chambers, an outer one-piece shell having a portion bulged outwardly of other portions thereof and having said other portions extending adjacent the wall-forming portions of the inner shell to provide double walls for said freezing chamber or chambers, the extending portions of said outer shell terminating with outwardly bulged portions, said first named outwardly bulged portion of said outer shell forming with a portion of the inner shell a header or manifold at the top of the freezing chamber, the end portions of 40 the inner shell and the outwardly bulged portions at the terminations of the outer shell being secured together and forming a second header or manifold at the bottom of the freezing chamber, and the portions of said outer shell extending from the first named header or manifold adjacent the wall-forming portions of the inner shell being secured to said inner shell at certain points and spaced therefrom at certain other points to provide refrigerant passages between 45 the shells, said passages connecting said first named header or manifold with said second named header or manifold.

3. A refrigerant containing evaporator including flat sheets of metal disposed adjacent each other and welded together, said assembled sheets forming two parallel vertical walls and a connecting bottom wall to provide an ice freezing container, corrugations formed in one of the sheets to provide a series of vertically-extending refrigerant passageways, headers formed at the upper ends of each of the parallel walls and connecting vertically-extending refrigerant passageways, refrigerant outlet means from said headers, an auxiliary header extending transversely of the passages and connecting the bottoms of passageways of both vertical walls, and an inlet conduit for conveying refrigerant to the evaporator, said inlet conduit extending into one of said vertical passageways near the top thereof to convey refrigerant downwardly to the auxiliary header and from thence upwardly through a plurality of the passageways in both vertical walls to said upper headers and from thence to said outlet means.

4. An evaporator for a refrigerating machine comprising complementary sheet metal portions at least one of which portions has an indentation formed therein providing a header, a plurality of refrigerant circulatory passages formed between said sheet metal portions and having their one ends communicating with said header below a normal liquid level to be maintained therein, the other ends of said passages being in open communication with each other at a point remote from said header, and means for discharging incoming liquid refrigerant to said evaporator into only a predetermined number of the total number of said plurality of refrigerant passages remote from and intermediate the point of communication of said other ends of said passages and the header, the remainder of said plurality of refrigerant passages providing unobstructed paths of flow for the free circulation of refrigerant between said header and the point of communication of the said other ends of said passages. 5
5. An evaporator for a refrigerating machine comprising complementary U-shaped sheet metal portions, at least one of said sheet metal portions having indentations formed therein providing a header adjacent the top of each leg of the U and a plurality of depending refrigerant circulatory passages communicating with said headers below a normal liquid level to be maintained therein, and means for discharging incoming liquid refrigerant to said evaporator into only a predetermined number of the total number of said plurality of refrigerant passages remote from and between said headers, the remainder of said plurality of refrigerant passages providing unobstructed paths of flow for the free circulation of refrigerant between said headers. 10
6. An evaporator for a refrigerating machine comprising complementary U-shaped sheet metal portions, at least one of said sheet metal portions having indentations formed therein providing a header adjacent the top of each leg of the U and a plurality of depending refrigerant circulatory passages communicating with said headers below a normal liquid level to be maintained therein, and means for discharging incoming liquid refrigerant to said evaporator into only a predetermined number of the total number of said plurality of refrigerant passages including a refrigerant conduit entering the wall of one of said headers and 15 passing downwardly through one of said passages to a point remote from and between said headers, the remainder of said plurality of passages providing unobstructed paths of flow for the free circulation of refrigerant between said headers, and means for removing vaporized refrigerant from the other of said headers. 20
7. An evaporator for a refrigerating machine including a pair of headers formed between complementary sheet metal portions, means including a plurality of refrigerant passages depending from and communicating with said headers below a normal liquid level to be maintained therein for circulating liquid refrigerant supplied to 25 said evaporator, a conduit connecting said headers above the liquid levels therein, and means for discharging incoming liquid refrigerant to said evaporator into only a predetermined number of the total number of said plurality of refrigerant passages remote from and between said headers, the remainder of said plurality of refrigerant passages providing unobstructed paths of flow for the free circulation of refrigerant between said headers. 25
8. An evaporator for a refrigerating machine comprising complementary U-shaped sheet metal portions, at least one of said sheet metal portions having indentations formed therein providing a header adjacent the top of each leg of the U and a plurality of depending refrigerant circulatory passages communicating with said headers below a normal liquid level to be maintained therein, a tube connecting said headers above the liquid levels therein, means for discharging incoming liquid refrigerant to said evaporator into only a predetermined number of the total number of said plurality of refrigerant passages including a refrigerant conduit 30 entering the wall of one of said headers and 35 passing downwardly through one of said passages to a point remote from and between said headers, the remainder of said plurality of passages providing unobstructed paths of flow for the free circulation of refrigerant between said headers, and means for removing vaporized refrigerant from the other of said headers. 40
